Rufus King INVENTOR.

BY
Joseph A. Miller ATTORNEY.

UNITED STATES PATENT OFFICE.

RUFUS KING, OF PLAINVILLE, MASSACHUSETTS, ASSIGNOR TO BUGBEE & NILES COMPANY, OF NORTH ATTLEBORO, MASSACHUSETTS.

RIBBON BRACELET.

REISSUED

1,406,647.

Specification of Letters Patent. Patented Feb. 14, 1922.

Application filed November 1, 1921. Serial No. 512,159.

To all whom it may concern:

Be it known that I, RUFUS KING, a citizen of the United States, residing at Plainville, in the county of Norfolk and State of Massachusetts, have invented new and useful Improvements in Ribbon Bracelets, of which the following is a specification.

This invention relates to certain new and useful improvements in ribbon bracelets and 10 pertains more especially to a bracelet of the ribbon type employed to attach a watch to the wrist of the wearer.

The primary object of the invention is to provide means for attaching the bracelet to 15 watches regardless of whether the attaching loops or eyes, which are secured to opposite sides of wrist watches for attaching purposes, are large or small, or in other words to provide watch attaching means which operate equally as well in the instance of 20 watches having small loops.

The invention further aims to provide means of the character mentioned which will effectively hold the watch against accidental 25 disengagement, and which can be cheaply constructed and easily operated and which is devoid of parts likely to become deranged.

Further and other objects will be later set forth and manifested in the course of the 30 following description.

In the drawings:

Figure 1 is a plan view of the invention, the watch and the ribbon being shown in dotted lines;

35 Figure 2 is a view of one of the attaching members showing a watch in fragment and in dotted lines, with a small eye or attaching loop;

Figure 3 is a section on line 3—3 of 40 Figure 1, and

Figure 4 is a like view on line 4—4 of Figure 1.

In proceeding in accordance with the present invention, the attaching members are 45 each composed of a base 1, slotted at 2, to receive the ribbon ends B therein, the latter being attached as usual. Extending outwardly from one side of the base 1 is a V-shaped keeper 3 which is connected to the base by arms 4, so that the keeper 3 is resiliently supported by the base so as to allow the keeper to move vertically, for a purpose shortly to be described. Extending outwardly from the opposite side 50 of the base 1 are a pair of outer hooks 5 with short bills and an intermediate hook 6

having a long bill, the latter lapping the nose or apex of the V-shaped keeper 3. As illustrated in the drawings all of the parts are made of integral or one piece construction, which thus provides a structure which can be economically produced, and which is devoid of any parts that are movable, except by or through the resilient property possessed by the metal from which the device is 60 formed. The bills of the hooks are preferably of curved cross-section as shown in Figures 3 and 4, and the bill 6 laps the V-shaped keeper 3 so as to prevent accidental disengagement of the watch eye or 65 loop when the latter is attached, as will now be described.

Referring to Figure 1 of the drawings it will be seen that the watch W has rather long loops L on each of its opposite sides, 70 so that each of the hooks 5—5 and 6 are engaged with the loops, the watch thus being supported on each side at three distinct points, accidental disengagement being prevented by the keepers 3, and hooks 6, each 75 of which latter lap the keepers.

In the instance of watches which have small loops such as L' in Figure 2, it will be seen that such loops are merely engaged by the hooks 6 with long bills, the loops 80 L' being disposed between the outer hooks 6. The invention thus operates with equal efficiency in the instance of watches with small attaching eyes or loops, as in those instances in which the eyes or loops are 85 large or elongated.

Having thus described my invention, what I claim as new and desire to secure by Letters Patent is:

1. In a wrist watch ribbon bracelet, an 90 attaching member composed of a base slotted to receive the ribbon and having a V-shaped keeper connected to one side of the base by outwardly extending arms, so as to support the keeper for resilient movement relative 95 to the base, and a pair of outer hooks with short bills and an intermediate hook with a long bill extending outwardly from the opposite side of the base and toward the keeper, the intermediate hook having its 100 long bill lapping the nose or apex of the keeper.

2. In a wrist watch ribbon bracelet, an attaching member composed of a base having a keeper resiliently supported by one side 105 thereof, and a pair of outer and an intermediate hook borne by the opposite side of

the base, the outer hooks having bills spaced from the keeper, and the intermediate hook having a long bill which laps the nose of the keeper.

5. 3. In a wrist watch ribbon bracelet, an attaching member composed of a base having a keeper resiliently supported by one side thereof, and spaced thereabove, and a multiplicity of hooks carried by the opposite side of the base, one of the hooks having its bill lapping the keeper, and other of the hooks being spaced from the keeper.

10 4. In a wrist watch ribbon bracelet, an attaching member composed of a base having a keeper, and a multiplicity of hooks one of which laps the keeper.

5. In a wrist watch ribbon bracelet, an attaching member composed of a base having a keeper, and a multiplicity of hooks one of which laps the keeper, and the others of 20 which are spaced from said one hook to allow an eye to be engaged with the last named hook and to lie between the other hooks.

25 In testimony whereof I have signed my name to this specification in the presence of two subscribing witnesses.

RUFUS KING.
